ENCLOSED CIRCUIT INTERRUPTER

Hans H. Willmann, Berlin-Charlottenburg, Germany, assignor to Westinghouse Electric & Manufacturing Company, East Pittsburgh, Pa., a corporation of Pennsylvania

Application May 1, 1941, Serial No. 391,249
In Germany March 6, 1940

15 Claims. (Cl. 200—153)

The invention relates to circuit breakers or switches of the enclosed type wherein the circuit breaker or switch unit is operable from outside the enclosing housing by an operating handle on the openable cover of the enclosing housing.

An object of the invention is the provision of an enclosed circuit interrupter of the class described having an improved operating drive whereby the interrupter is operated by the handle on the openable cover of the enclosing housing.

Another object of the invention is the provision of an enclosed circuit interrupter operated by an operating handle on the openable cover of the enclosing housing, wherein correct operative connection between the operating handle and the circuit interrupter mechanism is automatically established when the cover is closed even though the circuit interrupter and the operating handle are not in corresponding operating positions at the time the cover is being closed.

Another object of the invention is the provision of an enclosed circuit interrupter operated by an exterior operating handle on the openable cover of the enclosing housing which becomes automatically connected to the interrupter mechanism in correct relation thereto when the cover is closed regardless of the previous position of the handle, and without changing the position of the operating lever of the circuit interrupter.

Another object of the invention is the provision of an enclosed circuit interrupter embodying an improved separable coupling means between the circuit interrupter mechanism and the operating handle on the openable cover of the enclosure.

Another object of the invention is the provision of a circuit interrupter unit mounted in an enclosing housing having an openable cover and embodying an improved operating means for operating the interrupter by a handle on the cover, said operating means being very simple, compact, and inexpensive to manufacture.

In accordance with the invention, an operating handle is mounted on the openable cover of the enclosing housing, and this handle has a shaft rotatably mounted on the cover with its axis perpendicular to the plane of movement of the interrupter operating lever. The shaft extends inside the cover and has a coupling member secured thereto which is provided with a slot radial to the axis of the shaft for engaging a cross rod on the interrupter operating lever when the cover is closed. The coupling member also has guide surfaces on both sides of the radial slot leading to

the slot to guide the slot into engagement with the cross rod when the cover is closed.

The novel features that are considered characteristic of the invention are set forth in particular in the appended claims. The invention itself, however, both as to construction and operation, together with additional objects and advantages thereof will be best understood from the following detailed description of one embodiment thereof when read in conjunction with the accompanying drawings, in which:

Figure 1 is a side view, partly in section, of an enclosed circuit interrupter constructed in accordance with the invention; and

Fig. 2 is a plan view, partly in section, of the enclosed circuit interrupter.

Referring to the drawings, the reference numeral 5 generally designates an enclosing housing for protecting a circuit interrupter unit 7 which is mounted therein. The housing comprises a box-shaped metal casing 9 and a cooperating metal cover 11 which is hingedly mounted (Fig. 2) on one of the side walls of the casing 9 by a pair of hinges 13 (only one being shown) to permit the cover to be swung to open and to closed position.

The cover 11 is provided with a rim 15 which seats against the edges of the side and end walls of the casing 9, and also has an inwardly extending marginal flange 17 which overlaps the edges of the casing 9. A gasket 19 of resilient or elastic material is secured to the edge of the casing to seal the joint between the casing and cover. The housing serves to protect the circuit interrupter and any other electrical devices which may be mounted in the housing from dust, moisture, water and other deleterious materials which may be encountered in the usual applications of such apparatus. The cover 11 can be swung open to permit access to be had to the electrical devices within the housing, and may be locked closed by any suitable latching or locking device.

The circuit interrupter 7 may be a circuit breaker, switch, or manual motor starter of any known construction having an actuating handle or lever. The circuit interrupter illustrated is contained within its own casing and is provided with an oscillatable actuating lever 21 that is movable about a pivot 23 to opposite "off" and "on" positions to open and to close the contacts of the interrupter. The actuating mechanism of the circuit interrupter is preferably, but not necessarily, of the type which is automatically operable upon overloads to effect opening of the contacts, and the mechanism is resettable after

such automatic opening operation. There are a number of known circuit breakers of this general type, one, for example, being fully disclosed in Patent No. 2,048,114 to H. S. Gano et al., issued July 21, 1936.

An operating handle lever 25 is rotatably mounted on a hood-shaped portion 27 of the cover for operating the circuit interrupter from outside of the housing 5 when the cover is closed. The operating handle lever 25 is rotatable to "off" and to "on" positions corresponding to the "off" and "on" positions of the circuit interrupter lever 21 and is adapted to move the interrupter lever to its various operating positions through a separable automatic coupling means which will be hereinafter described. The cover 11 is provided with suitable indicia 28, such as "on" and "off", which cooperate with an index mark 29 on the operating handle to indicate the operating positions of the handle. The hood-shaped portion 27 is disposed over an opening 31 in the cover and is fastened to the cover by a pair of screws 33. An elastic packing 35 is disposed between the hood-shaped part 27 and the cover 11 to seal the joint therebetween.

The operating handle lever 25 is located on one side of the hood-shaped part 27 and has a shaft 37 secured at one end thereto which extends through bearing openings in the sides of the hood-shaped part 27 and is rotatable therein about an axis parallel to the pivot axis 23 of the interrupter actuating lever 21. The shaft 37 is preferably secured to the hub of the operating handle lever 25 by being die-cast therein so as to avoid any additional connection between these elements. The opposite end of the shaft 37 has an annular disk 39 mounted thereon, and the end of the shaft is spun over against this disk to retain the handle assembly in mounted position. To obtain a satisfactory water-tight and dust-tight joint at the bearing openings of the shaft, the side walls of the hood-shaped part 27 are provided with circular recesses 41 (Fig. 2) concentric with the shaft. A cylindrical neck 43 on the hub of the operating handle 25 fits in one of the recesses 41, and the disk 39 fits in the circular recess on the other side wall of the hood-shaped part 27. Preferably the recesses 41 are provided with circular slots 45 which are adapted to receive a lubricant to assist in sealing the bearing openings. The lubrication slots are sealed against the outside by the cylindrical neck 43 and the disk 39.

A coupling means is provided for automatically connecting the operating handle in corrective operative relation with the interrupter operating lever upon closing of the cover regardless of the previous relative positions of the handle and interrupter lever, that is, even though the handle may be in the extremely opposite operating position from the interrupter lever 21 before or during closing of the cover. This coupling means comprises a coupling member 47 connected with the shaft 37 inside of the cover for operatively engaging the interrupter lever 21 when the cover is closed. The coupling member 47 is preferably a double or U-shaped metal element, the legs of which are secured to the shaft 37 by square openings in the legs which engage a square portion of the shaft 37, as illustrated in the drawings. In accordance with the invention, each of the legs of the U-shaped coupling member 47 is provided with a slot 49 at the end thereof for engaging a cross rod 51 secured to the outer end of the interrupter lever 21. The slots 49 are dis-

posed radially with respect to the axis of rotation of the shaft 37; and the cross rod 51 on the interrupter actuating lever is disposed parallel to the axis of rotation of the shaft 37. Each of the 5 legs of the U-shaped coupling member 47 is formed to provide sloping guide surfaces 53 leading to the radial slots 49. The guide surfaces 53 are so arranged that during closing of the cover 11 the cross bar 51 will engage one or the other of the guide surfaces 53 and automatically cause movement of the operating handle 25 to a position corresponding to that of the interrupter lever 21, and thus automatically cause the slots 49 to engage the cross rod 51 to effect correct operative connection of the handle 25 with the interrupter lever 21. The operative connection takes place automatically regardless of the previous relative positions of the operating handle and the interrupter lever, that is, even though the operating handle may be in a directly opposite operating position from that of the interrupter lever at the time the cover is being closed. Preferably, the weights of the coupling member 47 and the operating handle lever 25 are made so that they balance each other, thus improving the operation of the coupling means. There is no spring between the coupling member 47 and the cover 11. It will be noted that with the construction of the present invention, the angle of inclination of the guide surfaces 53 with respect to the cross rod 51 is greatest when the handle is in one extreme operating position and the interrupter lever in the opposite extreme operating position, so that only relatively short guide surfaces are required to effect the automatic operative connection, even though the handle and interrupter lever are in directly opposite operating positions. Another advantage of the construction of the present invention is that it is possible to close the cover or to open it without changing the switching position of the interrupter actuating lever 21.

The cross rod 51 on the interrupter lever 21 preferably comprises a screw bolt 55 (Fig. 2) having a cylindrical head, and a cylindrical nut 57. The screw bolt 55 extends through a hole 59 in the interrupter lever 21, and the head of the screw bolt and the nut extend into recesses 61 on both sides of the interrupter lever 21. In this manner the thin connecting region of the bolt between the nut and the head of the screw bolt is maintained very short so that bending of the cross rod is avoided when the coupling member is moved.

While the invention has been disclosed in accordance with the patent statutes, it is to be understood that various changes in the structural details thereof may be made without departing from some of the essential features of the invention. It is desired, therefore, that the language of the appended claims be given the broadest reasonable interpretation permissible in the light of the prior art.

I claim as my invention:

1. An enclosed circuit interrupter comprising a housing having an openable cover, a circuit interrupter unit in said housing having a movable actuating member, an operating handle on the cover having a rotatable shaft extending inside the cover, and a coupling member secured to said shaft inside said cover and movable thereby parallel to the plane of movement of the interrupter actuating member, said coupling member having a slot therein radial to the axis of rotation of the shaft for engaging the interrupter actuating

member to couple the actuating member to the handle for movement thereby when the cover is closed and having guide surfaces on both sides of the radial slot leading to the slot.

2. In combination, an enclosing housing having an openable cover, a circuit interrupter unit mounted in the housing having a movable actuating member, an operating handle on the cover having a rotatable shaft extending inside the cover for moving the interrupter actuating member to operate the interrupter, a coupling member secured to said shaft inside the cover having a slot disposed radially with respect to the axis of the shaft and having guide surfaces on both sides of the radial slot leading to the slot, said interrupter actuating member carrying a cross rod parallel to said shaft which engages in the radial slot when the cover is closed.

3. In combination, an enclosing housing having an openable cover, a circuit interrupter unit mounted in said housing having a movable actuating member, an operating handle on said cover having a rotatable shaft extending inside said cover, means operable to automatically effect correct operative connection between said handle and said actuating member when the cover is closed irrespective of their previous relative positions before the cover is closed, said means comprising a coupling member secured to said shaft inside the cover having a slot therein radial to the axis of the shaft for engaging the interrupter actuating member and having guide surfaces on both sides of the radial slot leading to the slot.

4. In combination, an enclosing housing having an openable cover, a circuit interrupter unit in said housing having a movable actuating member, an operating handle rotatably mounted on the cover for operating the interrupter, and means automatically operable upon closing of the cover to cause the circuit interrupter and the handle to be respectively moved to corresponding positions regardless of their previous relative positions and to connect the handle with the interrupter actuating member, said means comprising a coupling member connected to said handle having a slot therein radial to the axis of rotation of the handle for engaging the interrupter actuating member and having guide surfaces on both sides of the radial slot leading to the slot.

5. In combination, an enclosing housing having an openable cover, a circuit interrupter unit in said housing having a movable actuating member, an operating handle rotatably mounted on the cover for operating the interrupter, and means automatically operable by the movement of the cover to closed position to cause movement of the handle to an operating position corresponding to that of the interrupter and to connect the handle with the interrupter actuating member, said means comprising a coupling member connected to the handle having a slot therein radial to the axis of rotation of the handle for engaging the interrupter actuating member and having guide surfaces on both sides of the radial slot leading to the slot.

6. In combination, an enclosing housing having an openable cover, a circuit interrupter unit in said housing having a pivoted actuating lever, an operating handle rotatably mounted on the cover about an axis parallel to the pivot axis of the actuating lever, means automatically operable upon closing of the cover to effect correct operative connection of the handle with the ac-

tuating lever regardless of their previous relative positions.

7. In combination, an enclosing housing having an openable cover, a circuit interrupter in said housing having a movable actuating member, an operating handle rotatably mounted in bearing means on the cover for operating the interrupter, a cross rod on said interrupter actuating member parallel to the axis of rotation of the operating handle, and a coupling member connected to said handle having a slot therein radial to the axis of rotation of the handle for engaging the cross rod when the cover is closed and having guide surfaces on both sides of the radial slot leading to the slot, said guide surfaces being disposed to cause the slot of the coupling member to automatically engage the cross rod when the cover is closed regardless of the previous relative positions of the handle and actuating member.

8. In combination, an enclosing housing having an openable cover, a circuit interrupter in said housing having a pivoted actuating lever, an operating handle rotatably mounted in bearing means on the cover about an axis parallel to the pivot axis of the actuating lever for operating the interrupter, a coupling member connected to said handle having a slot therein radial to the axis of rotation of the handle for engaging the actuating lever when the cover is closed and having guide surfaces on both sides of the radial slot for causing the slot to automatically engage the actuating lever upon closing of the cover regardless of the previous relative positions of the handle and actuating lever.

9. In combination, an enclosing housing having an openable cover, a circuit interrupter unit in said housing having a movable actuating member, a cross rod secured to said actuating member adjacent the outer end thereof comprising a screw bolt and a cylindrical nut extending out from lateral recesses on opposite sides of the actuating member, an operating handle rotatably mounted in bearings on the cover for operating the interrupter, and a coupling member connected to the handle having a slot therein for engaging the cross rod when the cover is closed and having guide surfaces on both sides of the slot to cause said slot to automatically engage the cross rod when the cover is set on the housing.

10. In combination, an enclosing housing having an openable cover, a circuit interrupter unit in said housing having a movable actuating member, a cross rod secured to said actuating member adjacent the outer end, an operating handle on said cover having a shaft rotatably mounted in bearing means in the cover and extending inside the cover, a U-shaped coupling member the legs of which are secured to the shaft, said coupling member having a slot at the end of each leg radial to the axis of said shaft for engaging said cross bar when the cover is closed and having guide surfaces on both sides of each slot for causing said slots to automatically engage said cross bar upon closing of the cover.

11. In combination, an enclosing housing having an openable cover, a circuit interrupter unit in said housing having a movable actuating member, said cover having a hood shaped portion, an operating handle on said cover having a shaft die cast therein at one end, said shaft extending through said hood shaped portion and being rotatably mounted in bearings therein, the

end of said shaft opposite the handle being spun over against a washer on the side of said hood shaped portion, and a coupling member secured to the shaft inside the cover having a slot therein radial to the axis of the shaft for engaging the actuating member upon closing of the cover.

12. In combination, an enclosing housing having a dome shaped portion, a circuit interrupter unit in said housing, an operating handle on said housing have a shaft secured at one end to said handle, extending through said dome shaped portion, and being rotatably mounted in bearings therein, the sides of said dome shaped portion through which said shaft extends having circular recesses therein concentric with the shaft openings, an annular slot on the inner surface of each recess for receiving a lubricant, said handle having a cylindrical neck which fits in one of said recesses, an annular disk on the shaft disposed in the other recess, means on the shaft engaging said disk for retaining said handle assembly in mounted position, and means for connecting the interrupter to said shaft for operation thereby.

13. In combination, an enclosing housing having an openable cover, a circuit interrupter unit in said housing having a pivoted actuating member, an operating lever pivotally mounted on the cover about an axis parallel to the pivot axis of the actuating member, said operating lever having a handle portion on the outside of the cover and having a coupling portion inside the cover, means operable upon closing of the cover to automatically effect correct operative connection between said operating lever and said actuating lever regardless of their previous relative positions, said operating lever being movable

freely unbiased by any spring when the cover is open.

14. In combination, an enclosing housing having an openable cover, a circuit interrupter unit in said housing having a pivoted actuating lever, operating means comprising an operating handle rotatably mounted on the cover about an axis parallel to the pivot axis of the actuating lever, and a coupling element inside the cover connected to the handle for movement therewith and having means engageable with the actuating lever to automatically effect correct operative connection of the handle with the actuating lever upon closing of the cover regardless of their previous relative positions, said handle and coupling element being freely movable and constructed to balance each other.

15. In combination, an enclosing housing having an openable cover, a circuit interrupter unit in said housing having a pivoted actuating lever, operating means comprising an operating handle rotatably mounted on the cover about an axis parallel to the pivot axis of the actuating lever, and a coupling element inside the cover connected to the handle for movement therewith, said coupling element having an open ended slot radial to the axis of rotation of the element engageable with the actuating lever when the cover is closed and having guide surfaces on both sides of the slot for automatically causing the slot to engage the actuating lever upon closing of the cover regardless of the previous relative positions of the handle and actuating lever, said coupling element and handle being movable freely and constructed to balance each other.

HANS H. WILLMANN.
